CAN HANDLING MACHINE

Leslie W. Hills, San Francisco, Calif., assignor to
 Hills Bros., San Francisco, Calif., a corporation
 of California

Application January 25, 1933, Serial No. 653,429

20 Claims. (Cl. 193—39)

My invention relates to means for handling cans, and is especially concerned with means for arranging cans in a single layer, into a plurality of layers, particularly for use in conjunction with 5 an associated machine such as the "Can casing machine" disclosed in Patent No. 2,013,408.

An object of the invention is to provide a can handling machine which is effective to distribute into a plurality of layers, successive cans arriving 10 at the machine in a single layer.

Another object of my invention is to provide a can handling machine in which cans are arranged in a plurality of layers or vertically spaced courses.

15 An additional object of the invention is to provide a can handling machine in which cans are divided into a plurality of layers, without deleterious effect upon the cans or jamming of the machine.

20 A further object of the invention is to provide a can handling machine capable of arranging cans in superimposed layers with a predetermined number of cans in each layer.

The foregoing and other objects are attained 25 in the embodiment of the invention shown in the drawings, in which—

Figure 1 is a side elevation of a can handling machine constructed in accordance with the invention and shown in one extreme position, also 30 called "full cycle" position.

Figure 2 is a side elevation similar to Figure 1 but showing the machine in another extreme position during an operating cycle.

Figure 3 is a cross-section the plane of which 35 is indicated by the line 3—3 in Figure 1.

Figure 4 is an elevation of an actuating cam, the view being in the direction of the arrow 4 in Figure 1.

Figure 5 is a diagram showing a runway switch 40 and the electric circuit of the machine.

In its preferred form, the can handling machine of my invention comprises an elevator adapted to receive cans in a single layer and to distribute the received cans into a plurality of superposed 45 layers, and includes means for maintaining a proper spaced relationship of the cans to preclude jamming and mutual interference and to segregate a predetermined number of cans in each layer.

50 In the form of mechanism disclosed in the accompanying drawings, I preferably provide a main framework, generally designated 6, composed of structural shapes such as channels and angles.

Leading into the framework 6 is an initial runway 7 which is inclined to the horizontal and

down which a succession of cans such as 8 rolls gravitally. Preferably, the runway 7 is inclusive of a multiplicity of can lines, in the present instance there being two parallel lines 9 and 10. Since the action of the mechanism is the same 5 with one or more such lines, but one is described herein in detail.

In the present instance, it is desired to divide cans arriving from each of the lines of the runway 7 into a plurality of separate superposed layers, and to this end I provide receiving ways 11, 12 and 13 respectively, which in the present instance are duplicate and in horizontal alinement with the lines 9 and 10. In vertical arrangement the ways are preferably disposed on the 15 framework 6 so that the center way 12 is in effect a continuation of the initial runway 7. Preferably, the ways 11, 12 and 13 lead into any suitable machine, not shown, for utilizing superposed layers of cans. Many such machines require cans 20 intermittently, and I therefore arranged that cans be discharged intermittently from the ways 11, 12 and 13 by a gate mechanism generally designated 14.

The framework 6 preferably carries a driving 25 shaft 16 connected directly or through transmission mechanism to any suitable source of motive power, not shown. An idler gear 17 is rotated in synchronism with the shaft 16 by means of a driving gear 18 mounted thereon. The idler gear 30 17 meshes with a gear 19 which is mounted on a shaft 21 journaled in the framework 6 and carrying a cam 22. Co-acting with the cam 22 is a follower 23 mounted on a shaft 24 and actuating a plunger 26. The plunger is connected by pivots 35 27, for instance, to each of a plurality of identical gate frames 28 which are pivotally mounted as at 29 on their respective can ways 11, 12 and 13. The frames 28 oscillate in unison about their respective pivot points 29 under the influence of 40 the plunger 26 and the cam 22. The gate frames 28 at their extremities carry cross rods 31 adapted to operate in slots 32 in the can ways 11, 12 and 13 and which rise and fall in order alternately to block and to free the ways 11, 12 and 13. 45 In accordance with the operation of this mechanism, therefore, cans resting in the ways 11, 12 and 13 are alternately blocked and released to roll gravitally down the respective ways.

I preferably interpose between the initial way 7 50 and the multiple ways 11, 12 and 13, a mechanism generally designated 33 for dividing and distributing the successive cans. The framework 6 is preferably provided with a plurality of uprights 34, each of which is equipped with a pair 55

of vertically aligned, anti-friction rollers 36. Adapted to run in the rollers 36 is a carriage 37 of generally quadrangular form in cross-section and on its central plane carrying box channels 38 adapted to fit into grooves in the rollers and to be guided thereby. Mounted on the carriage are horizontally duplicate runways 39 and 40 respectively, which in one extreme position of the carriage are adapted to be in substantial alignment with the ways 12 and 13 and in another position of the carriage to be in substantial alignment with the ways 11 and 12; that is, in one position of the carriage the runway 39 is in alignment with the way 1, while in the other position of the carriage the runway 40 is in alignment with the way 1.

In order to reciprocate the carriage 37 between its designated extreme positions, I preferably connect thereto, by means of a pivot 41 on a cross frame 42, a connecting rod 43. Mounted on an extension 44 of the framework 6 is a bell crank 46 which is pivoted as at 41 to the connecting rod 43 and is also provided with an arm 48. The bell crank is urged in one direction by a coil spring 49 connected to the arm 48 and likewise connected as at 51 to the framework 6 in order, partially at least, to counterbalance the carriage 37. A cross-shaft 52 not only carries the bell crank 46 but likewise has affixed thereto a depending lever 53 which is pivoted as at 54 to a rod 56 connected to a follower 57. The follower at its depending end is provided with a pivot 58 joined to the rod 56, and at its other end is pivoted by a pin 59 to a bracket 61 secured to the framework 6.

Interposed between the ends of the lever 57 is a cam follower, such as a roller 62, adapted to run in conjunction with a face cam 63 mounted on the shaft 21 and rotating therewith. As particularly disclosed in Figure 4, the cam 63 is disposed on the shaft 21 with an angular displacement from the cam 22. It will be noted that the cam 63 for substantially half of its circumference is virtually flat, as at 64, and that there is a peak 66 located substantially midway of the remaining portion of the circumference of the cam, with an incline 67 effecting a smooth merger of the surface 64 and the peak 66 on one side of the peak, while the other side of the peak merges with the surface 64 by means of an incline 68. With respect to the terminus of this surface the cam 22 is polarly displaced a small amount and in general is circular except for a radially depressed portion 69 which joins the general cylindrical surface of the cam 22 by means of merging faces 71 and 72 respectively.

The effect of the cams 22 and 63 and the described connecting linkage is such that, as the shaft 21 is rotated in time with the rotation of the shaft 16, the carriage 37 is initially moved from an uppermost or full cycle position, as indicated in Figure 1, to a lowermost position, as indicated in Figure 2. For substantially half of a revolution of the shaft 21 the carriage remains in the lower position of Figure 2, and finally moves from such lower position back to its upper or full cycle position as shown in Figure 1 where the cycle of operation is completed. Substantially as the carriage arrives at its uppermost position, the cam depression 69 permits the plunger 26 to descend and to lift the rods 31 into the path of cans on the ways 11, 12 and 13 and to block the descent of cans thereabove.

Effective upon cans which may attempt to enter the way 12 is a stop unit, generally design-

nated 80, comprising a cross rod 81 carried by a pair of crank plates 82. Each crank plate is pivoted as at 83 to the upper end of a lever 84 mounted on a pin 86 projecting from the framework 6. At its lower end, each lever 84 is connected to a rod 87 by a pivot 88, and each rod 87 is joined by a pin 89 to a bracket 91 mounted on the carriage 37. Each crank plate 82 is likewise pivoted as at 92 to a rod 93 joined by a pivot pin 94 to an extension 96 on the gate frame 14. As the shaft 21 rotates at the beginning of a cycle of operation, the depressed portions 69 of the cam 22 is moved from under the roller 23 and the cam lifts the plunger 26 to lower the rods 31 and permit cans previously restrained thereby to roll gravitally down the ways 11, 12 and 13. As the frame 14 oscillates in response to such lifting movement of the plunger 26, the extensions 96 pull the rods 93 to the left, as seen in Figure 2, and pivot the crank plates 82 about the pins 83 so that the rod 81 is moved in an arc downwardly and into the path of cans on the runway 40. Since the length of the runway 40 is preferably such as to accommodate a predetermined number of cans, in this instance three, the runways 25 39 and 40 are fully loaded when the carriage arrives in the position shown in Figure 2.

As the shaft 21 rotates upon the initiation of a cycle, the surface 63 rides under the roller 62. The carriage 37 descends and simultaneously the plunger 26 is raised to lower the rods 31 and release the cans disposed on the ways 11, 12 and 13. The combined movement of the carriage 37 and of the gate frame 14 is such that the plates 82 are pivoted about both their pivot points 92 and 83 35 so that the cross rod 81 descends with the carriage and assumes its position as shown in Figure 2. The cans which have been received on the runway 39 in its uppermost position, as shown in Figure 1, are lowered into registry with the way 13 40 and discharge from the runway 39 to the way 13. Simultaneously, the runway 40 has registered with the initial runway 7 and itself is charged with its allotted number of cans.

Upon continued rotation of the shaft 21, the surface 64 engages the roller 62 and for about a half rotation the carriage remains in lowermost position, but finally the surface 67 engages the roller 62 and, through the rod 56 and the crank 46, causes the rod 43 to lift the carriage 37 back 50 to its uppermost or full cycle position, as shown in Figure 1. During such ascending movement of the carriage the rods 87 are rendered effective upon the levers 84, and the plates 82 are caused to pivot at least partially about the pins 92, so 55 that the rod 81 in effect accompanies the leading can on the runway 40 in its ascending movement and not only retains the cans on the runway 40 but also prevents jamming of the leading can against the terminus of the way 11. The ratio 60 of ascending movement between the rod 81 and the carriage 37 is such that when the carriage has attained its uppermost position the rod 81 is substantially flush with the bottom of the runway 40 and releases the cans on the runway 40 to roll 65 gravitally onto the way 11.

Since the roller 62 and the roller 23 are at substantially right angles to each other, when the carriage 37 attains its uppermost position the depressed portion 69 of the cam 22 is effective upon the plunger 26 and causes the rods 31 to rise to block the cans just being received on the way 11, as particularly indicated in Figure 1. Simultaneously, in the uppermost or full cycle position of the carriage the runway 39 registers with 75

the initial runway 7 and permits cans to roll gravitally down to the stop rod 31 on the way 12, so that not only the upper way 11 but also the way 12 is loaded with a predetermined number of cans, and the carriage runway 39 also receives its complement of cans. This completes a single cycle of operation of the mechanism.

In order that the machine will function only when it is provided with a full supply of cans, I preferably provide a means on the runway 7 which is responsive to the presence of a can at rest. As particularly shown in Figure 5, the runway 7, and usually each line 9 and 10, is equipped with a plunger 101 which normally is urged upwardly into a position in which a switch 102 connected to the plunger is open. A ramp 103 is situated immediately in advance of the plunger and is so disposed that cans rolling down the runway even with a relatively slight velocity leave the ramp with such a trajectory as to clear the plunger 101 and to be ineffective on the switch 102. When the runway becomes substantially filled with cans, a succeeding can rolls over the ramp 103 and being stopped by cans ahead of it comes to rest on the plunger 101. The weight of such can is ample to depress the plunger and to close the switch 102. The driving motor 104 for the machine is in circuit with the switch 102 and with leads 106 and 107 extending to a source of electricity. Likewise, a master switch 108, which can be operated or controlled in any convenient manner, for instance, as shown in the co-pending Hills and Clark patent, above identified, is interposed in the circuit of the motor 104. When the switch 108 is closed, the motor 104 is effective to operate the machine when the switch 102 is closed. Because of this mechanism, the machine rests between cycles of operation until sufficient cans are present for a succeeding cycle and under no circumstances will operate if there is a deficiency of cans.

If desired, barriers or blocks can be placed selectively in one or more of the runways 39 and 40, as well as in the ways 11, 12 and 13 to render ineffective any one or more of the can lines.

The device of my invention, when functioning as described, is effective to divide cans arriving in a single layer, into a plurality of superposed layers—in this instance three—, and is effective not only so to distribute the cans but also to maintain the cans at all times in such position that they do not interfere with each other nor jam in any portion of the machine. The runways are at a gentle inclination so that the cans are handled without harm. Furthermore, the cans are distributed in predetermined lots to each of the discharging ways for subsequent handling in an associated machine.

I claim:

1. A can handling machine comprising a runway for cans, a reciprocating elevator, a pair of superposed ways on said elevator adapted alternately to register with said runway, and superposed can receiving ways adapted to register with both of said elevator ways coincident with registration of either of said elevator ways and said runway.

2. A can handling machine comprising an elevator adapted to reciprocate between two extreme positions, a pair of superposed ways on said elevator, a runway adapted to register with one of said ways in one of said extreme positions and to register with the other of said ways in the other of said extreme positions, and a plurality of superposed ways some of which are adapted to register

with both of said ways in both of said extreme positions.

3. A can handling machine comprising an elevator adapted to reciprocate between two vertically spaced extreme positions, a pair of inclined vertically spaced ways on said elevator, an inclined runway adapted in each of said extreme positions to register with a different one of said ways, and a plurality of inclined ways, a different pair of which is adapted to register with said elevator ways in each extreme position of said elevator.

4. A can handling machine comprising an initial runway adapted to support rolling cans, a plurality of receiving ways for supporting rolling cans, a reciprocating elevator for transferring cans from said runway to said ways, and means operating in time with the reciprocation of said elevator for periodically blocking cans rolling on said ways.

5. A can handling machine comprising an initial runway for rolling cans, a plurality of receiving ways for rolling cans, means for blocking cans rolling on said ways, a reciprocable elevator for transferring cans from said runway to said ways, and means for reciprocating said elevator and synchronously operating said blocking means.

6. A can handling machine comprising a reciprocable elevator, inclined ways for rolling cans on said elevator, means for restraining cans on said ways, and means for simultaneously reciprocating said elevator and operating said restraining means.

7. A can handling machine comprising a reciprocable elevator, inclined ways for rolling cans on said elevator, means adapted to move adjacent said ways for restraining cans from rolling thereon, and means for reciprocating said elevator and synchronously moving said restraining means.

8. A can handling machine comprising an initial runway for rolling cans, a plurality of receiving ways for rolling cans, means for blocking cans rolling on said ways, a reciprocable elevator, inclined ways for rolling cans on said elevator, means for restraining cans on said elevator ways, and means for reciprocating said elevator, operating said blocking means and operating said restraining means in synchronism.

9. A can handling machine comprising an initial runway for rolling cans, a plurality of receiving ways for rolling cans, oscillating means for blocking cans rolling on said ways, a reciprocable elevator, inclined ways for rolling cans on said elevator, means adapted to move adjacent said elevator ways for restraining cans on said elevator ways, means for reciprocating said elevator, means for oscillating said blocking means in synchronism with said reciprocating means, and means for moving said restraining means in synchronism with said reciprocating means.

10. A can handling machine comprising an initial runway for rolling cans, a plurality of receiving ways for rolling cans, oscillating means for blocking cans rolling on said receiving ways, a reciprocable elevator, inclined ways for rolling cans on said elevator, means adapted to move adjacent said elevator ways for restraining cans on said elevator, means for oscillating said blocking means, and linkage connected to said elevator and to said blocking means for moving said restraining means.

11. A unit handling machine comprising a reciprocable member, ways on said member, means

5

10

20

25

30

35

40

45

50

55

60

for restraining units on said ways, receiving ways, means for restraining units on said receiving ways, and means for synchronously reciprocating said member and operating said restraining means.

12. A can handling machine comprising a plurality of receiving ways, an initial runway for cans, a reciprocating elevator interposed between said initial runway and said receiving ways, a pair of ways on said elevator, stops on said receiving ways, and means for reciprocating said elevator between two extreme positions in each of which a different one of said elevator ways aligns with said initial runway to charge said receiving ways with a complement of cans resting against said stops.

13. A can handling machine comprising a runway for cans, a plurality of rails disposed to support cans with their rolling axes horizontal and arranged to provide a plurality of superposed ways, a vertically reciprocable elevator interposed between said runway and said ways, and superposed ways on said elevator adapted to transfer cans from said runway to each of said ways, said reciprocable elevator registering in either extreme position with said runway and a plurality of said superposed ways.

14. A can handling machine comprising an initial runway, a plurality of rails disposed to support cans with their rolling axes horizontal and arranged to provide a plurality of superposed ways, reciprocating means interposed between said runway and said ways, and superposed ways on said elevator for transferring cans from said runway to said ways, said reciprocating means in either extreme position registering with the initial runway and a plurality of receiving ways.

15. A can handling machine comprising a runway for cans, a reciprocating elevator, a pair of superposed ways on said elevator adapted alternately to register with said runway, and superposed can receiving ways adapted to register with both of said elevator ways coincident with registration of either of said elevator ways and said runway.

16. A can handling machine comprising a runway for cans, a reciprocating elevator, means for reciprocating said elevator, a pair of superposed ways on said elevator adapted alternately to register with said runway, superposed can receiving ways adapted to register with both of said

elevator ways coincident with registration of either of said elevator ways and said runway, and means responsive to the stoppage of a can on said runway for controlling said reciprocating means.

17. A can handling machine comprising a runway for cans, a reciprocating elevator, electrical means for reciprocating said elevator, a pair of superposed ways on said elevator adapted alternately to register with said runway, superposed can receiving ways adapted to register with both of said elevator ways coincident with registration of either of said elevator ways and said runway, and an electric circuit controlling switch in the path of a can stopping on said runway for controlling said electrical reciprocating means. 15

18. A can handling machine comprising a runway for cans, a reciprocating elevator, electrical means for reciprocating said elevator, a pair of superposed ways on said elevator adapted alternately to register with said runway, superposed can receiving ways adapted to register with both of said elevator ways coincident with registration of either of said elevator ways and said runway, an electric circuit for said electrical reciprocating means, a switch in said circuit, and a 25 second switch in said circuit in the path of a can stopping on said runway.

19. A can handling machine comprising a runway for cans, a reciprocating elevator, a pair of superposed ways on said elevator adapted alternately to register with said runway, superposed can receiving ways adapted to register with both of said elevator ways coincident with registration of either of said elevator ways and said runway, electrical means for reciprocating said elevator, a circuit for said electrical means, and a plurality of switches in said circuit, one of said switches being responsive to the stoppage of a can on said runway.

20. A can handling machine comprising a plurality of receiving ways including an intermediate receiving way, an initial runway for cans, a reciprocating elevator interposed between said initial runway and said receiving ways, a plurality of superposed ways on said elevator, means for reciprocating said elevator between two extreme positions, and means for charging said intermediate receiving way with a full complement of cans when said elevator is in one of said extreme positions. 50

LESLIE W. HILLS.
